UNITED STATES PATENT OFFICE.

JAMES CAVANAGH, OF BOSTON, MASSACHUSETTS, ASSIGNOR TO UNITED SHOE MACHINERY COMPANY, OF PATERSON, NEW JERSEY, A CORPORATION OF NEW JERSEY.

SHOE.

1,229,585.

Specification of Letters Patent. Patented June 12, 1917.

Application filed September 30, 1914. Serial No. 864,274.

To all whom it may concern:

Be it known that I, JAMES CAVANAGH, a citizen of the United States, residing at Boston, in the county of Suffolk and State of 5 Massachusetts, have invented certain Improvements in Shoes, of which the following description, in connection with the accompanying drawings, is a specification, like reference characters on the drawings indicating 10 like parts in the several figures.

This invention relates to the manufacture of shoes and has for its object to effect an economy and an improvement. The invention consists in an improved shoe. In 15 women's light shoes for indoor and dress wear, chiefly but not exclusively turn shoes, there have been used for many years heels having body portions consisting of wood and covered with leather. These covered heels 20 are produced as a distinct branch of the trade, the wooden body portions being cut to shape and the covering of sheet material being applied, usually with paste or glue, over the periphery of the heel and lapped inwardly over the seat face of the heel so that 25 no portion of the wooden body shall remain exposed which will be visible after the heel has been attached. The usual standard has been to use a covering of leather or other material which will harmonize with the material of the shoe vamp and for this purpose 30 kid leather and satin and other cloths have most commonly been employed, although sheet rubber and celluloid have been proposed as has also enamel which has been 35 baked on the heel.

This method of manufacturing heels involves a high labor cost, making this class of heels expensive to the shoe manufacturer 40 who must also make allowance for the damage of a substantial percentage of finished heels in the attaching operation. Furthermore, these heels are lacking in durability because the covering material is easily sus- 45 ceptible of injury and possesses very little wearing quality when subjected to the use which the heel of a shoe receives. Also moisture readily softens the attaching paste or glue and allows the covering to loosen and 50 become detached from the heel body. Rubber, celluloid, and enamel covered heels are open to serious objections which will be at once apparent.

These conditions of high cost and lack of

durability of finish have restricted the use of 55 wood heels within very narrow limits so that it is estimated that only a small fraction of a per cent. of the shoes made are provided with wood heels.

One of the apparently permanent standards as to footwear is that the heel and the vamp shall appear to consist of material of similar nature. Thus a black shoe is furnished with a black heel and if the vamp is of enameled leather the heel is polished. 60 while if the vamp has a dull finish the heel is given a dull surface; tan shoes have tan heels and rubber heels are colored and finished to resemble the appropriate appearance of a leather heel for which they are substituted. 65 70

It is the object of my invention to produce a wood heel which shall answer to the above standard as perfectly as heels made entirely of leather can be made to do, and which has 75 the very important commercial advantages of great economy and as high a degree of durability as is found in leather heels.

A feature of my invention is a shoe having 80 a wood heel with a peripheral surface provided with a film of carnauba wax forced into the surface of the work by rubbing pressure while the wax is in a heated condition, the wood heel having a surface appearance harmonizing with that of the vamp of the 85 shoe.

The invention will now be described in connection with the accompanying drawing and will then be pointed out in the claims. 90

Fig. 1 is a perspective view of a wood heel produced by the wood working machinery of wood heel manufacturers.

Fig. 2 shows the shoe after the heel has been attached and fitted to its shoe and 95 scoured in accordance with this invention.

Fig. 3 represents the same shoe after the heel has been stained in accordance with this invention.

Fig. 4 represents the shoe after the wood heel has been treated with heat and wax in accordance with this invention and has been 100 surface finished to match the vamp of the shoe.

In making my improved shoe a wood heel 105 2, preferably of well-seasoned, fine-grained hard wood, such as the best quality of maple, is taken by the shoe manufacturer as it

comes from the woodworking machinery of the wood heel manufacturer, see Fig. 1, is provided with a leather toplift 3 and is attached to a shoe 4 in the usual way by nail-
5 ing. The heel is then trimmed to the contour of the shoe, if necessary, to adapt that particular heel to the shoe of which it is to be a part. This step has not before been possible because the heels were covered be-
10 fore being attached in order that the covering could be lapped over the upper edge of the heel and its edge hidden between the seat face of the heel and the shoe bottom. After the heel has been attached and is in
15 satisfactory shape, the heel is scoured, this operation being preferably finished on very fine emery cloth or paper as, for example, that designated in the trade as "No. 150", until a soft satin-like surface is produced
20 on the wood as in Fig. 2. It is important that this surface be secured alike on the sides of the heel where the surface usually runs "with the grain" and on the back and breast of the heel where the surface usually runs
25 across the grain. A satisfactory surface having been secured, a stain is applied in which has been incorporated a material adapted to unite or bind together the surface fibers of the wood. A stain answering
30 to these requirements and with which desired results have been obtained includes a coloring ingredient, which may be either lamp black or a dye such as one of the anilin dyes, soap and carnauba wax boiled with a
35 diluent until the wax has become completely incorporated in the stain. This stain is applied to the satin-like surface of the heel of the shoe, care being taken to obtain such a thorough coating of the heel with the stain
40 as to produce a uniform surface on all parts of the heel when the stain has dried. The stain preferably is allowed to dry thoroughly and then the heel of the shoe, Fig. 3, is subjected, in the presence of heat, to
45 rubbing pressure. The heat melts the wax and the rubbing pressure appears to cause the wax completely to bind or unite together the fibers of the surface of the wood and the top lift and to produce a continuous
50 hard even surface capable of taking a surface finish which may vary from a dull finish to match a dull leather vamp, or a fabric such as that of the cloth quarters of the illustrated shoe, to a high gloss, as
55 indicated in Fig. 4 to match a patent leather vamp 6 of the shoe shown. The pressure and heat appear to cause the wax to be forced into the surface of the heel so as to produce an entirely permanent connection of the
60 wax to the heel. This heating and rubbing treatment is advantageously produced by the use of a heated iron rotated in contact with the heel and in practising this invention the best results have been obtained by me from
65 a combined beating and rubbing action

which seems to drive the hot wax into the surface with good effect, this action being produced by an irregular surfaced rubbing iron, but of course being capable of being produced by hand tools. Preferably additional wax is applied to the wood heel besides that which was incorporated in the stain and I have secured the best results by applying additional carnauba wax in a hot condition. Advantageously the wax is melted and is applied hot and with pressure by the heated rubbing instrument. After the described application of the wax the desired surface appearance, Fig. 4, is produced by friction with materials selected according to the luster desired as a brush of long flexible bristles for a dull surface to match fabric or mat kid leathers and a soft rag finishing roll to produce a gloss to match enameled leathers. As has been intimated, some of the advantages of the invention may be obtained by applying all of the wax at one time either with the stain or while the wood heel is being subjected to the action of heat and rubbing pressure. I prefer, however, to apply a moderate amount of wax incorporated in the stain and to apply additional wax during the heat treatment.

My invention has among others the following advantages: The heels can be taken from the heel manufacturer in the condition in which they came from the wood working machinery, that is, at the stage at which they represent their minimum value, and attached directly to the shoe. Thus, if the heel is damaged by splitting or otherwise before it is ready to finish it represents the minimum loss. After attachment to the shoe the heel can be shaped to it with precision; can be scoured and in all respects finished with relation to the other portions of the particular shoe of which it is to be a part, and this work can be done under the shoe manufacturer's directions instead of being done in the heel factory and due regard can be paid to the shoe of which it is to become a part. While there are advantages, as above suggested, in attaching the heel to the shoe before the heel is scoured, it is within my invention, in its broader aspects, to defer attaching the heel until one or all of the steps in the finishing operation have been performed.

The finish produced on my novel wood heels is entirely durable, being substantially unaffected by moisture. One of the exceedingly important characteristics of these heels is that they have all the desirable features and appearance of leather heels. It will be plain that their appearance can be restored by treatment similar to that given the leather vamp by the hand of a bootblack.

While I have described the application of carnauba wax as made first in the stain and again during the treating of the wood

heel with heat and pressure, the heel of my invention may be produced by applying the carnauba wax at one time only, either with the stain alone or after the application of the stain. While the time at which the wax is applied to the wood heel admits of variation, it appears to be essential, in order to obtain on wood heels a finish which is satisfactory under the conditions of use to which these heels are subjected, to work the carnauba wax into the surface of the heel by heat and pressure, preferably rubbing pressure by means of a heated instrument, after which the desired surface appearance can be reproduced whenever the heel requires cleaning during the wear of the shoe. The cost of finishing wood heels in accordance with this invention is less than one-quarter that of covering wood heels and is low enough to make very profitable the substitution of the heel produced in accordance with this invention in place of leather heels.

The novel process of manufacturing shoes disclosed herein forms the subject-matter of my divisional case, Serial No. 52,645, filed Sept. 25, 1915.

Having explained this invention and described the best way now known to me to produce my improved shoe heel, I claim as new and desire to secure by Letters Patent of the United States:—

1. In a shoe, a heel constructed of wood the peripheral surface of which has been provided with a film coating of carnauba

wax so finished that its appearance harmonizes with that of the vamp of the shoe.

2. A shoe heel made of stained wood, the peripheral surface of said heel on its sides and rear end being satin-like and having the surface fibers bound down by a coating or carnauba wax burnished so that the wood has a surface appearance harmonizing with that of a leather shoe vamp.

3. In a shoe a wood heel having a peripheral surface coated with a film of wax forced into the surface of the wood by rubbing pressure in the presence of heat, whereby the cross-grained portions of the peripheral surface are rendered identical in appearance with the straight-grained portions.

4. In a leather shoe, a wood heel provided with a leather top lift, the peripheral surface of said heel and top lift having a satin-like surface coated with a film of carnauba wax whereby the periphery of the top lift and the cross-grained and straight-grained portions of the peripheral surface of the wooden heel are rendered identical in appearance with one another and with the vamp of the shoe.

In testimony whereof I have signed my name to this specification in the presence of two subscribing witnesses.

JAMES CAVANAGH.
